UNITED STATES PATENT OFFICE.

FREDERICK J. WEBER, OF LOS ANGELES, CALIFORNIA, ASSIGNOR TO THE WEBER INCINERATOR CO., A CORPORATION OF CALIFORNIA.

SLAB INCINERATOR WITH INTERCONNECTED DOOR CONTROL.

Application filed June 29, 1925. Serial No. 40,270.

This invention relates to the construction of incinerators, and particularly to incinerators designed for domestic use.

With the passage of city ordinances respecting the disposal of refuse, it has become necessary to provide improved means for the burning of waste material. A common type of incinerator consists of a vertical structure of fire-resisting material, having an opening 10 near the upper end thereof, through which the material to be burned may be introduced, and having an opening near the bottom thereof, to serve as a draft opening and for the removal of ashes. These comparatively primitive incinerators are not generally made of such size as to receive a very large charge and, as the material placed therein burns, it is customary to add thereto, through the charge openings; but it is found that, when 20 the fire is burning within the incinerator and the charge door is open, flames and smoke will issue therefrom in such manner as to make the addition of more material unpleasant and even dangerous. It is therefore an object of this invention to provide an improved incinerator, having a charging opening provided with a suitable door or cover, and a draft opening having a closure plate, optionally associating therewith intervening 25 means for causing a closing movement of said plate, relatively to the draft opening, when the charging door is opened—thus momentarily shutting off the air from the incinerator, so as to cause the flames therein to 30 die down, obviating the undesirable and dangerous issuance of smoke and flame from the charging opening.

It is a further object of this invention to provide simple and effective means whereby 40 the opening of a charging door and the closing of a draft opening may be simultaneously accomplished, as by hand (or by the foot) of the person desiring to place material, to be burned, in the incinerator. This feature is 45 an important convenience, owing to the fact that the arms of the user are generally occupied in carrying and holding the material to be burned.

The major parts of my incinerator may be 50 cast in the form of separate slabs and plates, suitable for economical transportation and convenient assembly, interlocking to form a rigid structure; and it is a further object of this invention to provide novel features contributing to the simplicity and economy

and durability of construction of slab incinerators.

It is a further object of this invention to provide an incinerator so constructed that a clean-out door, extending the full width of 60 the incinerator, may be provided,—giving ample room for the removal of ashes from the bottom of the incinerator and permitting a grate-supporting structure to be entirely removed from the interior thereof. Owing 65 to the packing of material in an incinerator for burning, a free upward circulation of air, for combustion, is often seriously interfered with; and it is an object of my invention to obviate such interference, as by providing parts effectively cooperating with a novel grate and draft system hereinafter described.

Other especial advantages and objects of my invention may be best understood from 75 the following description of typical embodiments of my invention, taken in connection with the appended claims and the accompanying drawings, in which—

Fig. 1 is a perspective view of a preferred 80 form of a complete incinerator.

Fig. 2 is a vertical section through an incinerator of the type shown in Fig. 1.

Fig. 3 is a section, on a slightly enlarged scale, which may be regarded as taken on the 85 plane indicated by the line 3—3 of Fig. 2, but omitting details irrelevant to slab and plate relationships.

Fig. 4 is a similar view, taken substantially as indicated by the line 4—4 of Fig. 2. 90

Fig. 5 is a fragmentary sectional view, taken in such a plane as is indicated by the lines 5—5 of Figs. 1 and 2.

Fig. 6 is a separate elevational view, on an enlarged scale, of a feed door and door frame, 95 the frame being cast into a slab.

Fig. 7 is a detail view, taken substantially as indicated by the arrow 7 of Fig. 6.

Fig. 8 is a perspective view of a closure element such as may optionally be provided 100 for use, without pivots, in one of the slabs comprising an incinerator cap, as herein-after described.

The incinerator shown in Fig. 1 comprises a lower tier of slabs constituting a box structure 11, an upper tier 12, and a cap tier 13, preferably formed of separate slabs or blocks, above which extends a stack 14,—the slabs of the respective tiers being of such form that they interlock without the use of 110

bolts and provide an incinerator chamber in which refuse may be burned without fire hazard.

In this form of incinerator, the lower section 11 is formed of four quadrilateral slabs 16, 17, 18 and 19, which are preferably cast from concrete, or the like; and these slabs, which may rest upon a divided or unitary slab or foundation member 20, are preferably upwardly convergent or trapezoidal and provided with mating side or edge formations of the general character shown at 23, Fig. 3,—such that an interlocking effect and a seal may be formed therebetween, with or without the use of a layer 24 of asbestos or other similar fire-resisting incombustible fibrous substance. Two of the mentioned slabs of a tier, as the slabs 16 and 18, may be slightly wider and adapted to overlap the edges of the interposed slabs; and beveled surfaces thereof may provide channels 26, cast therein. The edges 27 of the members 17 and 19 are also shown as correspondingly beveled, in planes which may intersect substantially at the center of said incinerator, to provide shoulders having obtuse angles that interfit within the channels 26,—incidentally effecting a bending of any sheet 24 of asbestos, or the like, placed between adjacent slabs, and preventing any slab from swinging inward between its neighbors, although permitting any slab to shift independently and directly outward, without a resultant fracture of interfitting parts.

The lower edges of the respective slabs may be held in place by means such as upwardly extending flanges 30 on the foundation plate 20; and frames or apertured horizontal restraining plates 31, 31', also optionally cast of a composition such as concrete, may be placed over the upper edges of any of the respective tiers of slabs. The frame or plate 31 is shown as recessed, at 33 and 34, so that it will provide a flange 34', to fit down over the upper edges of the slabs 16 to 19 inclusive, and the flange 33', to receive the lower edges 35 of the slabs 37, constituting the upper section 12. Thus, the respective tiers of slabs may oppositely contact with an inwardly extending flange 36; and the upper edges of the slabs 37 may be enclosed by the similar plate or frame 31', comprising downwardly extending flanges 38,—upwardly extending flanges 38' being shown as partially overlain by interfitting sections 39 of the cap 13. This cap may be of frusto-pyramidal form, and may comprise four substantially identical slabs each overlapping one adjacent slab and carrying an upwardly projecting internal arcuate flange 40, over which the lower end or bell 41 of the stack 14 may extend. The wall members or slabs 37 may have the same edge construction as the described slabs 16 to 19 inclusive, and may be placed together, with or without strips of

interposed fibrous insulating material, in the general manner above described. The stack 14 may be surmounted by any suitable spark arrester 42, this being optionally carried by a bead or removable collar 43.

The slab 19, as best shown in Figs. 1 and 5, may comprise a lintel section 19^a, which extends only part way down from the top edge of the lower section 11, being supported on upwardly and outwardly inclined surfaces S 70 at the edges of slabs 16 and 18,—so that a clean-out opening 44, which extends the full width of the section 11, is thereby formed; and a closure section 19^b, for this opening, may be provided with a cast-in handle H, and 75 may rest upon foundation plate 20. The beveled and upwardly inclined surfaces 45 and 46 are preferably non-contacting even when the section 19^b is in closed position. As indicated, the section 19^a is intended to have 80 a greater horizontal length than the section 19^b, which may interfit between adjacent sections 16 and 18, substantially in the manner indicated in Figs. 1, 3 and 5,—so that it may either be pivotally swung outward or 85 be completely removed. In view of the fact that the edges of the wall slabs converge upwardly and inwardly in a manner favorable to support the section 19^b, it will be evident that this member will remain in place without 90 the use of securing means.

In the described form of incinerator, the slab 16 may be provided, at or near its lower edge, with a draft opening 47 having a closure plate 48, operating in cast-in slides 49; and a front slab 37 of the upper section 12 may be provided with a charging opening encircled by a suitable frame 50,—about which the body of one of the slabs may be cast. Supported near the lower edge of the opening, 100 as by trunnions 51, is shown a door 52; and a flattened portion 53 of one of said trunnions may be vertically movable through a slot 54 in one of a pair of bearing lugs 55, said slot being too narrow to receive said trunnion 105 except when the door 52 is held in a substantially horizontal plane. By thus pivoting the door 52 on a horizontal axis near its lower edge, I am enabled to use this door as a feed chute; and, to avoid a jarring effect incidental 110 to the opening of said door. I may optionally surround one or both of the trunnions 51 with spiral springs S', substantially as shown, optionally utilizing also means such as the bent wire shown, to keep the trunnion 55 115 from jumping out through slot 54.

From, for example, an eye 56 movable with or by a handle 57, a chain 59, or other flexible member, may extend directly past a projecting ledge (optionally reinforced at 62 as 125 shown in Figs. 1 and 2) this chain being secured to the closure member 48 and of such length that when the door 52 is in closed position the draft plate 48 is raised,—thus allowing the passage of air through the draft 130

opening 47 whenever the charging door is closed. A bracket 64 may be secured to the plate 48, or its equivalent, if desired, to facilitate the operation of the interconnected closure members by foot pressure; and, in any event, the described interconnection of parts causes the draft to be shut off when the charging door is open, thus preventing the issuance of a blast of flame or smoke from the charging opening, and making it possible safely and conveniently to place additional refuse in the incinerator.

As shown, I prefer to connect the mentioned closures by attaching the chain 59, directly or indirectly, near the respective upper edges thereof; and for the sake of completeness, I may mention at this point certain auxiliary or cooperating features of construction comprise substance to the protection of which Patent No. 1,575,024 granted March 2nd, 1926 is more especially directed. As shown in Fig. 2, a grate support 75, of heavy sheet metal or other suitable material, may be placed in the bottom of the lower section 11, and may have substantially the form shown, a one-piece or other grate 76 being disposed thereon, for the purpose of supporting the materials placed in the incinerator. The grate support 75 may comprise an upper U-shaped frame 77, below which extend inwardly directed horizontal webs 78, from the inner edges 79 of which there may extend downwardly and outwardly inclined side walls 81, sloping in such manner that the lower edges 82 thereof may be disposed almost vertically below the outer edges of the U-shaped frame 77. The grate support 75 is intended to be placed with its central or leg-connecting portion disposed opposite the opening 47, or its equivalent, so that V-shaped channels are provided between side walls 81 and the lower portions of the wall slabs 17 to 19 inclusive,—air passages such as perforations 84, being provided in the upper portions of the sloping walls 81, through which air, entering by way of the draft opening 47 into the mentioned channels, may pass inwardly to the central portion of the grate 76, somewhat as indicated by the arrows 87, in Fig. 2. Upon removal of the section 19^b, which is shown as extending substantially the full width of the lower portion of my incinerator, ample opening is provided, through which the grate support and grate may be bodily removed with a minimum of effort,—so that all metallic or other incombustible scrap, cans and similar articles, may be cleaned from the grate and the ashes quickly shoveled or dragged out with a hoe or other suitable tool. The features here referred to constitute a valuable advance over the known types of incinerators,—not commonly provided with laterally removable grate supports nor with suitable means for cleaning out the ashes or other unburnable articles therefrom.

In conjunction with the described features, or independently thereof, I may employ in the cap 13, even though the same be formed in the sectional manner illustrated, an additional closure 88, not provided with hinges, 70 although preferably secured against misplacement by means such as a chain 89, shown as surrounding the stack 14, and as secured to a handle 90, bolted or otherwise secured near the top of said closure. The closure 75 plate 88, or its equivalent, may be used for any desired purpose, as for the insertion of wet waste above dry waste introduced through opening 50; and it may be provided with reinforcing ribs 91 near the upwardly convergent lateral edges thereof; and said reinforcing ribs may be cut away near the top and expanded at their lower ends, in order to facilitate the removal or the seating of the same in an aperture 92, within which the described ribs may loosely fit.

It will be understood that any or all of my described slabs and plates may be left unprovided with interior reinforcement, and any of the described tiers or courses of blocks may be 90 adapted to interfit either in the general manner illustrated in Fig. 3 (two of the blocks being wider than the intervening blocks) or in the general manner illustrated in Fig. 4 (in which each block extends completely over 95 one edge of one adjacent block); but I prefer that my blocks shall meet in broken diagonal planes forming an angle of about 45° relatively to vertical planes which include the horizontal edges thereof, and it should be 100 understood that, when local regulations permit, the lower portion of one of my incinerators, preferably including an apertured plate 31 (and optionally employed with a sheet metal or other suitable cover, not shown) 105 may be used alone; or, the upper portion, including parts above the plate 31, may be used independently of the described lower portion and associated parts. In any event, the slab-retaining flanges, extending upwardly and downwardly from the respective plates 20, 31 and 31', or their equivalents, are intended to provide ample space or clearance (as at 93, 94, 95, 96, and 97, Fig. 2) to permit unavoidable expansion of the respective slabs 110 whose outward movements are restrained thereby; and the annular spaces between the upwardly extending flanges mentioned and the slabs retained therein may advantageously be filled with sand, or the like, tending not 115 only to prevent leakage of smoke, but to restore the respective inclined slabs, under the action of gravity, to inner positions such as those illustrated in Fig. 2; but it should be generally understood that various features 120 of my invention may be independently employed, and also that numerous modifications, additional to those described, might be devised, by those skilled in the art to which this case relates,—without the slightest departure 125 130

from the spirit and scope of my invention, as the same is indicated above and in the appended claims.

I claim as my invention:

5. 1. In an incinerator, the combination of: substantially flat, separate wall members of trapezoidal outline arranged for placement in edge engagement so as to form an enclosure; foundation means having upwardly extending projections limiting separative outward movement of the lower edges of said wall members; and means comprising a polygonal horizontal frame preventing outward movement of the upper edges of said wall members, said trapezoidal members meeting in broken planes formed by interfitting, obtuse-angled shoulders, so disposed as to permit each trapezoidal member to shift independently and directly outward.
10. 2. In an incinerator, the combination of: wall members of quadrilateral outline arranged for placement in edge engagement so as to form an enclosure; foundation means having upwardly extending projections preventing outward movement of the lower edges of said wall members; and a frame resting on the upper edges of said wall members, said frame having downwardly extending flanges for preventing outward movement of the upper edges of said wall members and having upwardly directed flanges; an upper section comprised of cooperating quadrilateral wall members having their lower edges resting on said frame within the confines of said upwardly directed flanges; and a cap supported above the upper edges of said upper section and having downwardly extending interfitting parts.
15. 3. In an incinerator, the combination of: wall members of quadrilateral outline arranged for placement in edge engagement so as to form an enclosure; means for preventing outward movement of the lower edges of said wall members; a frame resting on the upper edges of said wall members, said frame having downwardly extending flanges for limiting outward movement of the upper edges of said wall members, and having upwardly directed flanges; an upper section comprised of cooperating quadrilateral wall members having parts adapted to interfit with a cap and having their lower edges resting on said frame within the confines of said upwardly directed flanges; and a sectional cap supported above said interfitting parts at the top of said upper section.
20. 4. In an incinerator, the combination of: wall members of quadrilateral outline, arranged for placement in edge engagement so as to form an enclosure; foundation means having upwardly extending projections preventing outward movement of the lower edges of said wall members; one of said wall members comprising a fixed upper lintel section, leaving a clean-out opening which extends the full width of said enclosure, and a closure section, resting on said foundation means but engaging beneath said lintel section and normally closing said clean-out opening; and means preventing outward movement of the upper edges of said wall members.
25. 5. An incinerator comprising: a tier of flat, trapezoidal side slabs upwardly tapering and convergent, the abutting lateral surfaces thereof being formed to interfit in broken vertical diagonal planes provided by beveled edges thereon, some of said planes intersecting the substantially vertical axis of said incinerator; and interfitting means for limiting outward movement of the horizontal edges of said slabs.
30. 6. An incinerator comprising: flat, trapezoidal side slabs upwardly tapering and convergent, the abutting lateral surfaces of said slabs being formed to interfit in vertical diagonal planes provided by beveled edges thereon, some of said planes intersecting the substantially vertical axis of said incinerator; apertured restraining means extending across said slabs, the tops and bottoms of said slabs being substantially horizontal and retained within recesses in said restraining means.
35. 7. An incinerator comprising: inclined slabs disposed in tiers and provided with interlocking abutting lateral vertical surfaces provided by beveled edges thereon, some of said surfaces being disposed in planes which intersect substantially in the substantially vertical axis of the said incinerator; and apertured restraining composition plates interposed between successive tiers of the said slabs.
40. 8. An incinerator as defined in claim 7 in which said plates comprise inwardly extending flanges contacting with horizontal edges of said slabs.
45. 9. An incinerator comprising: flat, trapezoidal side slabs beveled in broken planes providing obtuse shoulders which permit independent expansion of said slabs without separation thereof but which tend to prevent direct passage of smoke laterally between said slabs.
50. 10. An incinerator comprising: flat, trapezoidal side slabs beveled in broken planes providing obtuse shoulders which permit independent expansion of said slabs without separation thereof but which tend to prevent direct passage of smoke laterally between said slabs and to retain fibrous combustible material therebetween.
55. 11. An incinerator comprising: slabs so disposed as to form inwardly extending walls of an enclosure; and a restraining plate, said plate being provided with a flange normally spaced from said slabs and with means, held thereby, adapted to prevent said slabs from moving toward an outer position.
60. 12. An incinerator comprising: plates provided with restraining flanges; a tier of up-

wardly convergent slabs held between said plates and providing an enclosure; one of said slabs including an upper lintel section, permanently held in place, and a section normally under said lintel section, which is outwardly movable by pivoting the same upon its lower edge to provide a clean-out opening, said upper section being retained by engagement with upwardly and outwardly inclined surfaces upon adjacent slabs.

13. An incinerator comprising: apertured plates; superimposed tiers of upwardly convergent slabs restrained by flanges on said apertured plates, one of said tiers comprising slabs respectively having an arcuate projection at the upper edges thereof; and a stack fitting over said projections.

14. An incinerator comprising: apertured plates; superimposed tiers of upwardly convergent slabs restrained by flanges on said apertured plates, one of said tiers comprising slabs respectively having arcuate projections at the upper edges thereof; a stack fitting over said projection; a spark arrester and means for supporting said spark arrester at the top of said stack.

15. An incinerator comprising: a tier of flat, trapezoidal side slabs upwardly tapering and convergent, the abutting lateral surfaces thereof being formed to interfit in broken vertical diagonal planes provided by beveled edges thereon, some of said planes intersecting the substantially vertical axis of said incinerator, said beveled edges providing interfitting means for limiting outward movement of the horizontal edges of said slabs and in which each slab completely overlaps one end of one adjacent slab.

16. An incinerator comprising: plates provided with retaining flanges; a tier of upwardly convergent slabs held between said plates and providing an enclosure, one of said slabs including a lintel section permanently held in place forming a "clean-out" opening therebelow into said enclosure; and a cover section for said opening which is outwardly movable by pivoting the same upon its lower edge.

In testimony whereof, I have hereunto set my hand at Los Angeles, California, this 22nd day of June, 1925.

FREDERICK J. WEBER.
